(57) **CLAIM**

The ornamental design for a wireless end node, as shown and described.

DESCRIPTION

FIG. 1 is a front perspective view of a wireless end node module showing our new design;
FIG. 2 is a top elevational view thereof;
FIG. 3 is a bottom elevational view thereof;
FIG. 4 is a front side elevational view thereof;
FIG. 5 is a rear side elevational view thereof;
FIG. 6 is a right elevational view thereof; and,
FIG. 7 is a left elevational view thereof.

Surface shading in the FIGS. 1-7 is provided to show clearly the character and contour of all surfaces of any three-dimensional aspects of the design.

The broken lines shown in the FIGS. 1-7 are for illustrative purposes only and forms no part of the claimed design.
